The ornamental design for a ski pole, as shown and described.

DESCRIPTION

FIG. 1 is a front view of a ski pole showing my new design;

FIG. 2 is a side view thereof, the other side being a mirror image thereof;

FIG. 3 is a top plan view thereof;

FIG. 4 is a rear view thereof;

FIG. 5 is an enlarged partial front view of the lower portion of the ski pole;

FIG. 6 is a side view thereof;

FIG. 7 is a top view thereof;

FIG. 8 is a rear view thereof;

FIG. 9 is a bottom plan view thereof; and,

FIG. 10 is a cross-section taken along line 10—10 of FIG. 6.
